TRANSMISSION CONTROL IN SIGNALING SYSTEMS

Nathaniel C. Norman, New York, N. Y., assignor to Bell Telephone Laboratories, Incorporated, New York, N. Y., a corporation of New York

Application December 27, 1933, Serial No. 704,124

4 Claims. (Cl. 179—170)

The invention relates to two-way signaling systems and particularly to circuits for controlling transmission in said systems.

An object of the invention is to improve the operation of long two-way signaling systems employing signal-controlled switching circuits for suppressing echoes and preventing singing.

To obtain proper operation of long two-way signaling systems, for example, long four-wire toll telephone circuits, it has been found desirable in the past to utilize in connection therewith signal-controlled switching apparatus for effectively disabling one of the associated two-wire paths while signal transmission is taking place over the other, so as to prevent echo current or reflected current from being transmitted back to the transmitting end of the system and causing a disturbance or singing. The disabling apparatus usually comprises means, such as an amplifier-rectifier control circuit, for diverting a portion of the signal current from one path and utilizing it to cause the oppositely directed path to be open-circuited or short-circuited, or to insert a large loss in the oppositely directed path by properly controlling the operation characteristics of an amplifier therein.

In certain circuits of the prior art, these signal-controlled devices, or echo suppressors as they are commonly called, one of which is associated with each two-wire path, are located at some intermediate station, for example, at a midway point. In other circuits of the prior art the two units of the echo suppressor are located respectively at or near the terminals of the four-wire circuit.

In accordance with the present invention, in two-way signaling systems of the above described types, transmission lockouts are minimized and break-ins are facilitated by making the operation of the echo suppressors depend on the relative amplitude level of waves in the two one-way amplifying paths. In one embodiment applicable to a four-wire telephone system employing terminal echo suppressors, at each terminal waves from the incoming and outgoing one-way paths are fed into a balance circuit which controls the suppressor at that terminal. The balance circuit at each terminal is initially adjusted so that when the relative amplitude levels of the waves in the incoming and outgoing paths are such as would be obtained by the presence in the former of speech currents of the subscriber associated with the distant terminal and in the latter only of reflected or echo currents due to said speech currents, the state of balance

in the balance circuit at the near terminal is such as to allow normal operation of the echo suppressor thereat to suppress the echo path. Now if the subscriber associated with the near terminal starts to talk, a portion of his speech currents will be impressed on the balance circuit at that terminal along with the echo currents of the first subscriber and will so change the balance of the balance circuit as to disable the echo suppressor. Thus, the outgoing path will become operative to transmit the second subscriber's speech currents to the first subscriber so that the latter will know the former is trying to break in. A singing loss element is normally included in the output of each one-way path and is removed by operation of the echo suppressors. As long as both subscribers continue to talk at the same time, therefore, both suppressors will be disabled and each subscriber will hear the speech of the other attenuated by the singing loss. As soon as one subscriber stops to listen, the balance of the balance circuit at his terminal is restored and the circuit functions normally again.

The objects and advantages of the invention will be better understood from the following detailed description thereof when read in connection with the accompanying drawings in which

Fig. 1 shows schematically a four-wire toll telephone circuit equipped with transmission control circuits in accordance with the invention;

Fig. 2 shows in greater detail a preferred construction of the transmission control circuits utilized in the system of Fig. 1.

The diagram of Fig. 1 is not an actual circuit diagram but rather a single-line layout, each line indicating a transmission path. A normal break in a path is indicated by separated arrow heads; a normal make by contacting arrow heads. To show that a transmission element is to be controlled by a device an arrow points from the device towards the element. An arrow directed at a make point indicates that the path will be disabled at that point by operation of the control device and an arrow directed at a break point indicates that the break in the path will be eliminated by operation of the control device. A resistance element in a path indicates a finite loss in the path. A resistance element shown bridged between the break points in a path indicates that the path is not disabled but that there is a finite loss normally in the path which is effectively eliminated when the control device operates to eliminate the break.

The four-wire telephone circuit of Fig. 1 comprises a one-way transmission path EA includ-

ing the one-way amplifying devices A_1 and A_2 for repeating telephonic currents in the direction from west to east between the west two-way line section L_w and the east two-way line section L_E , and the one-way transmission path WA including the one-way amplifying devices A_3 and A_4 for repeating telephonic currents in the direction from east to west between the east two-way line section L_E and the west two-way line section L_w . The oppositely directed one-way repeating paths EA and WA may be connected in substantially conjugate relation with each other and in energy transmitting relation with the west line section L_w and the east line section L_E , respectively, for example, by hybrid coil transformers and associated balancing networks or other suitable means (not shown).

Connected across the path WA near the west terminal of the four-wire circuit is the input link 1 of the echo and singing suppressor S_1 which is adapted to respond to telephone signals received from WA to disable the path EA near its input by opening the normally closed contacts 2 therein, and substantially simultaneously to remove effectively the singing loss 3 from the output of WA by closing the normally open switch contacts 4 in shunt with the loss. Similarly, connected across the path EA near the east terminal of the four-wire circuit is the input link 5 of the echo and singing suppressor S_2 adapted to respond to telephone signals from EA to disable the path WA near its input by opening the normally closed contacts 6 therein, and substantially simultaneously to remove effectively the singing loss 7 from the output of the path EA by closing the normally closed contacts 8 in shunt with the loss. The echo and singing suppressors S_1 and S_2 may be of any of the well known types.

Bridged respectively across the output of the path WA at a point near the input to the amplifier A_4 and across the input of the path EA at a point near the input to the amplifier A_1 are the input links 9 and 10 to the balancing mechanism BM_1 which is adapted to operate automatically in response to applied waves of a single frequency f_1 , preferably outside the normal range of the telephone signals transmitted over the paths WA and EA , to continuously adjust the potentiometer 11 in link 9 until the amount of signal energy entering the balancing mechanism BM_1 from the path WA over link 9 is very nearly equal to the amount of echo energy due to the signals in WA entering BM_1 from the path EA over link 10.

Bridged respectively across the link 9 in the output of the potentiometer 11 and across the input of the link 10 are the input links 12 and 13 to the balanced disabler BD_1 . The balanced disabler BD_1 is adapted to operate in response to signal currents entering the link 12 by way of link 10 from the path EA , to disconnect the input of the echo and singing suppressor S_1 from the path WA by opening the normally closed contacts 14 in the link 1, either when no signals are being transmitted over the path WA , or when the amount of energy received by the link 12 through link 10 from the path EA is greater than that received by the link 13 through link 9 from the path WA .

Bridged respectively across the output of the path EA at a point in the input to the amplifier A_2 and across the input of the path WA at a point in the input to the amplifier A_3 are the input links 15 and 16 to the balancing mechanism BM_2 which is adapted to operate in response to

applied waves of a single frequency f_2 , preferably outside the normal range of the signals transmitted over the paths WA and EA , to continuously adjust the potentiometer 17 in the link 15 until the amount of signal energy entering the balancing mechanism BM_2 from the path EA over link 15 is very nearly equal to the amount of echo energy due to the signals in EA entering BM_2 from the path WA over link 16.

Bridged respectively across the link 15 in the output of potentiometer 17 and across the input of link 16 are the input links 18 and 19 to the balanced disabler BD_2 . The balanced disabler BD_2 is adapted to operate in response to the signal currents entering link 18 by way of link 16 from path WA , to disconnect the input of the echo and singing suppressor S_2 from the path EA , by opening the normally closed contacts 20 in the link 5, either when no signals are being transmitted over the path EA , or when the amount of energy received by the link 18 through link 16 from the path WA is greater than that received by the link 18 through link 15 from the path EA .

A tone source 21 is adapted to be connected across the input of the path WA at a point in the output of the echo suppressor contacts 6 therein, by means of the key 22, to send out over the path WA a tone of the frequency f_1 to which the balancing mechanism BM_1 at the west terminal of the four-wire circuit is responsive.

A tone source 23 is adapted to be connected across the input of the path EA at a point in the output of the echo suppressor contacts 2 therein by means of the key 24, to send out over the path EA a tone of the frequency f_2 to which the balancing mechanism BM_2 at the east terminal is responsive.

The preferred construction of the portion of the control circuits schematically shown within the dot-dash box 25 or 25' in Fig. 1 is shown in Fig. 2.

As indicated in Fig. 2, the balancing mechanism BM_1 consists of a motor driven device for controlling the setting of the adjustable loss pad 11 and a control circuit for controlling its operation.

The loss pad 11 in the input link 9 comprises a potentiometer consisting of a resistance 26 connected across the link 9, and an adjustable arm 27 contacting therewith and which is adapted to be rotated either in a forward or reverse direction in response to rotation of the shaft 28 on which it is mounted, to control the setting of the potentiometer and accordingly the attenuation in the link 9. Two discs, 29 and 30, are suitably mounted on the shaft 28 so as to be rotatable therewith. The discs 29 and 30 are adapted to be selectively brought into engagement with the constantly rotating disc 31 driven by the motor 32, under control of the electromagnets 33 and 34, respectively.

The control circuit of the balancing mechanism BM_1 includes a differential relay 35 with the two equal magnetically opposed windings 36 and 37. The winding 36 is adapted to be energized by the output current of the vacuum tube rectifier 38 the input of which is coupled through a selective circuit 39 adapted to select the frequency f_1 , to the link 9 in the output of the loss pad 11. The winding 37 is adapted to be energized by the output current of the vacuum tube rectifier 40, substantially identical with the rectifier 38, the input of which is coupled through the selective circuit 41, identical with the selective circuit 39, to the link 10. The differential relay 35 is

equipped with contacts 42 which when closed completes an energizing circuit for the electromagnet 33 from the battery 43, and with contacts 44 which when closed complete an energizing circuit for the electromagnet 34 from the battery 43.

The balanced disabler BD₁ comprises a differential relay 45 with two equal and magnetically opposed windings 46 and 47. The winding 46 is adapted to be energized by the output current of the vacuum tube rectifier 48 the input of which is coupled through the amplifier 49 in the link 13 across the link 9 in the output of loss pad 11. The winding 47 is adapted to be energized by the output current of the vacuum tube rectifier 50 the input of which is coupled through the amplifier 51 in the link 12 to the link 10 in front of the selective circuit 41. The differential relay 45 is equipped with normally closed contacts 14 which are adapted to be opened to break the circuit of the input link 1 when the magnetic force of winding 47 predominates over that of the winding 46 to the required degree in response to a suitable difference between the amplitude level of the energizing currents supplied to the windings 46 and 47.

The control circuits within the dot-dash portion 25' near the east terminal of the four-wire circuit are the same as shown in Fig. 2 except that the selective circuits in BM₂ corresponding to the circuits 39 and 41 in BM₁ would be designed to be selective to the tone frequency f_2 instead of f_1 .

The operation of the system will now be described by reference to Figs. 1 and 2. It will be assumed first that no speech waves are being received over the two-wire lines L_W and L_E by the one-way transmission paths EA and WA. A tone of the frequency f_1 is then sent over path WA by connecting the tone source 21 to WA by means of key 22. At the west terminal a portion of the tone energy is diverted into the link 1 and operates the echo and singing suppressor S₁ provided contacts 14 are closed. A second portion of the tone energy is transmitted through the singing loss 3 in the path WA provided contacts 4 are open. Part of this latter portion is diverted into the link 9 and is attenuated by potentiometer 11 therein and the attenuated tone in the output of potentiometer 11 divides. One part is selected by the selective circuit 39 and is rectified by the vacuum tube rectifier 38 causing the winding 36 of the differential relay 35 in the balancing mechanism BM₁ to be energized. The other part of the tone f_1 enters the input link 13 and is amplified by the amplifier 49 and rectified by the vacuum tube rectifier 48 causing the winding 46 of the differential relay 45 in the balanced disabler BD₁ to be energized. A third portion of the tone energy of frequency f_1 is amplified by the amplifier A₁ in the path WA and passes out of the four-wire circuit through the hybrid coil connection to the two-wire line L_W and returns in the form of an echo to the path EA. A portion of the echo energy will be diverted into link 10 from the path EA and will be divided between the balance mechanism BM₁ and the balanced disabler BD₁. One part is selected by the selective circuit 41 and is rectified by the vacuum tube rectifier 40 causing the winding 37 of the differential relay 35 in the balancing mechanism BM₁ to be energized. The other part of the echo energy enters link 12, is amplified by the amplifier 51 and rectified by the vacuum tube rectifier 50 causing the winding 47 of the differential relay 45 in the balanced disabler BD₁ to be energized.

If the amount of tone energy entering the vacuum tube rectifier 38 in link 9 is greater than that entering the vacuum tube rectifier 40 in link 10, the magnetic force of winding 36 will predominate over the opposing magnetic force of winding 37 and the relay contacts 42 will close, causing the electromagnet 33 to be energized by current from battery 43. Disc 29 on the shaft 28 will then be brought into engagement with the continuously rotating disc 31 thereby causing the arm 27 of the potentiometer 11 in the input link 9 to be rotated by shaft 28 in a counter-clockwise direction to increase the attenuation in the link 9. This will continue until equality is established between the magnetic forces of the windings 36 and 37 of the differential relay 35 whereupon the relay contacts 42 will be opened causing the energizing current to be removed from electromagnet 33 and the connection between the motor and the potentiometer 11 to be broken.

If the amount of tone energy entering the vacuum tube rectifier 40 is greater than that entering the vacuum tube rectifier 38, the magnetic force exerted by winding 37 will predominate over that exerted by winding 36 and relay contacts 44 will close, causing battery 43 to energize the electromagnet 34. The electromagnet 34 will then bring disc 30 into engagement with the continuously rotating disc 31, thereby rotating the arm 27 of the potentiometer 11 in a clockwise direction and decreasing the attenuation in the link 9 until equality is established between the magnetic forces of the windings 36 and 37 of the differential relay 35. The relay contacts 44 will then return to the open condition causing relay 34 to be deenergized and thus the adjustment of the potentiometer 11 to be stopped.

As soon as the balancing mechanism BM₁ has completed the above described operations, key 22 is opened, thereby disconnecting the tone source 21 from the path WA.

Meanwhile, the balance mechanism BM₂ and the control circuits therefor at the east terminal may be adjusted by a tone of a single frequency f_2 sent over the path EA from the tone source 23 in a manner similar to that just described for the corresponding apparatus at the west terminal of the four-wire circuit.

The apparatus at the two terminals of the system is now in adjustment for proper operation of the echo and singing suppressor for signal transmission in either direction.

It will now be assumed that speech waves for transmission from east to west are received over the two-wire line L_E and are impressed through the hybrid coil or other coupling on the transmission path WA at the east terminal of the four-wire circuit, and at that time no speech waves have as yet been received at the west terminal from the two-wire line L_W for transmission from west to east over the path EA.

The received speech waves will be amplified by the amplifier A₃ and transmitted over the path WA toward the west terminal of the four-wire circuit. At the west terminal a portion of the speech wave energy will be diverted into the link 1, and, the contacts 14 therein being closed will cause operation of the suppressor S₁ thereat, simultaneously closing the contacts 4 to remove effectively the singing loss 3 from the output of the path WA, and opening the contacts 2 in the input of the path EA thereby preventing transmission of echoes due to the west to east speech currents over the path EA. A second portion of the speech wave energy in the path WA will be

diverted into the link 9 where it will be attenuated by the potentiometer 11. This portion will be blocked from the input to the balancing mechanism BM₁ by the selective circuit 39, and will enter the input link 13 of the balanced disabler BD₁, where it will be amplified by amplifier 49, rectified by the vacuum tube rectifier 48 and will cause the winding 46 of the differential relay 45 to be energized. A third portion of the speech wave energy, after passing out of the four-wire circuit into the two-wire circuit L_w through the hybrid coil connection will return to the four-wire circuit in the form of echo and enter the path EA. A portion of the speech echo will be diverted into the link 10 and, being blocked from the input to the balancing mechanism BM₁ by the selective circuit 41 therein, will enter the input link 12 to the balanced disabler BD₁. The echo currents in link 12 will be amplified by amplifier 51 and rectified by the vacuum tube rectifier 50 causing the winding 47 of the differential relay 45 to be energized.

Because of the previously described adjustment of the balancing mechanism BM₁ in response to the tone f_1 from the tone source 21, the magnetic forces due to the rectified speech waves in the windings 46 and 47 of the differential relay 45 will in effect cancel each other and the contacts 14 will remain in the normal closed position. Thus, the echo and singing suppressor S₁ will remain connected to the path WA and will function in the usual manner in response to the speech waves received over the path WA and diverted into the link 1 near the west terminal to suppress echoes in the path EA and to remove the singing loss from the path WA.

Now, let it be assumed that there is an appreciable pause in the speech waves received over the two-wire line L_E and that during the pause speech waves from a west subscriber are received over the two-wire line L_w and are impressed on the input of the transmission path EA at the west terminal of the four-wire circuit.

A portion of the received speech energy will be diverted from EA into the link 10 and, being blocked from the balancing mechanism BM₁ by the selective circuit 41, will enter the link 12 of the balanced disabler BD₁. In the link 12, the speech energy will be amplified by the amplifier 51 and rectified by the vacuum tube rectifier 50 causing the winding 47 of the differential relay 45 to be energized. Since the amplifier A₄ prevents any portion of the speech wave energy received over the two-wire line L_w from reaching the link 9, no magnetic force is developed in the winding 46 of the differential relay 45 in the balanced disabler BD₁. Therefore the magnetic force in winding 47 of the relay 45 will cause the contacts 14 in link 1 to open, disabling the suppressor S₁.

The remaining portion of the speech waves received from the two-wire line L_w will be amplified by the amplifier A₁ and sent over the path EA in the direction from west to east. A portion will be diverted at the east terminal into the link 5 and cause operation of the suppressor S₂ to simultaneously open contacts 6 to disable WA from transmitting echoes of the west subscriber's speech to the east subscriber, and to close contacts 8 in EA effectively removing the singing loss 7 from that path. Another portion of the speech waves in EA will be diverted at the east terminal into the link 15 and, being blocked from the balancing mechanism BM₂ by the selective circuit in the input thereof, will enter the input

link 18 to the balanced disabler BD₂. Another portion of the speech currents will pass from the output of EA into the two-wire line L_E, return to WA in the form of echo currents, and will be diverted into link 16. This portion also will be blocked from the balancing mechanism BM₂ by the selective circuit in its input, but will enter the other input link 19 of the balanced disabler BD₂. Because of the previous adjustment of the balancing mechanism BM₂ in response to the single frequency tone f_2 transmitted over EA, the magnetic forces resulting from the two inputs to the balanced disabler BD₂ effectively cancel each other, and the echo and singing suppressor S₂ will remain connected to the path EA through the closed contacts 20 in the link 5.

It will now be assumed that speech waves for transmission from east to west are received from the subscriber associated with the two-wire line L_E and are impressed on the input of the transmission path WA, and that at first no speech waves are being received from the west subscriber at the west terminal over the two-wire line L_w, so that the east subscriber gets control of the switching circuits at both ends of the system in the manner which has been described. Then let it be assumed that after an interval and while the east subscriber is still talking, the west subscriber starts to talk.

The west subscriber's speech waves will be diverted at the west terminal into the link 10 and thus into link 12 where after amplification and rectification it will be supplied to the winding 47 of the differential relay 45 in the balanced disabler BD₁ where it will add to the magnetic force of that winding which is already energized by the echo currents due to the east subscriber's speech waves. Since the amplifier A₄ prevents any portion of west's speech wave energy received over the two-wire line L_w from reaching the link 1 connected to the path WA, no additional magnetic force is developed in the winding 46 of the differential relay 45 in the balanced disabler BD₁; therefore contacts 14 are broken under control of the superior magnetic force of winding 47, and the echo and singing suppressor S₁ will be disconnected from the link 1. The echo suppressor contacts 2 in the path EA will then return to the closed condition allowing west's speech current, as well as east's echo currents to be transmitted over that path to the east terminal, and contacts 4 in WA will return to the open condition re-inserting the singing loss 3 in that path.

When west's speech waves and east's echo currents transmitted over the path EA reach the east terminal the portion of the energy diverted into link 5 cannot cause operation of the suppressor S₂ because the balanced disabler BD₂ has previously operated under control of east's speech waves to disable that suppressor by opening contacts 20 in the link 5. The singing loss 7 therefore is effective in the output of path EA. This loss together with the equal loss 3 effective in the output of path WA is sufficient to prevent the gain around the four-wire loop from exceeding zero decibels and thus prevents singing. West's speech waves and east's echo currents encounter an attenuation in EA identical with that encountered by east's speech currents and west's echo currents in WA. When west's speech waves and east's echo currents reach the link 15, a portion of their energy is diverted and enters the balanced disabler BD₂ in which its effect is exactly offset by the waves entering the balanced disabler

BD₂ through the link 16 which comprise echoes of west's speech waves and echoes of east's echo waves.

Thus, with the circuits of the invention, whenever both subscribers talk at once and speech waves are being received in the four-wire circuit simultaneously from the subscribers associated with the two-wire lines L_W and L_E, the suppressors at both terminals are disabled and speech waves and accompanying echoes are transmitted simultaneously in both one-way transmission paths EA and WA, attenuated only sufficiently to prevent singing of the four-wire circuit. When speech waves are received over only one of the two-wire lines at a time, operation of the circuit is similar to that of any four-wire circuit equipped with standard types of terminal echo and singing suppressors. It follows that two subscribers associated with the terminals of a four-wire circuit equipped in accordance with the invention can both talk at once without either locking the other out, irrespective of the relative starting times of either subscriber's speech waves. Thus, either subscriber can let the other know that the former wants to break in.

In the preferred form of the invention which has been illustrated and described, the tone sources utilized for adjusting the balancing mechanisms are shown as connectable to the one-way transmission paths at the distant ends of the paths from the mechanisms which they control. It is also within the scope of the invention to have the tone sources connectable to points at the near ends of the one-way paths, for example, in WA near the point of connection of link 1 or 9 thereto, and in EA near the point of connection of link 5 or 15 thereto. Also it would be within the scope of the invention to have the tone sources connected to the one-way transmission paths automatically instead of by keys, for example, by suitable connections to extra leaves on the terminal jacks of the four-wire circuit.

It is also within the scope of the invention to use a vacuum tube vario-losser of the type described in the copending application of L. F. Smith, Serial No. 676,113, filed June 16, 1933, in place of the motor and magnetic clutch operated potentiometer described herein, or to adjust the potentiometer 11 by manual means to obtain equal magnetic forces in the two windings of the differential relay in BD₁ or BD₂ when incoming signals are present in the incoming one-way path at a terminal and echoes only of said signals in the outgoing one-way path thereat, in which case the balancing mechanisms BM₁ and BM₂ and associated control circuits and even the tone sources 22 and 23 may be eliminated.

The frequency of the tones utilized to initially adjust the control circuits at the two terminals may be within the frequency range of the transmitted signals if suitable means are provided for preventing false operation by the signals of those frequencies, for example, such as disclosed in the U. S. patent to N. C. Norman No. 1,918,822, issued July 18, 1933, for a similar purpose.

Other modifications of the circuits illustrated and described within the spirit and scope of the invention will occur to persons skilled in the art.

70 What is claimed is:

1. In combination, a four-wire circuit comprising two oppositely directed one-way paths for repeating signals in opposite directions between two two-way circuits, a switching device connected to one of said paths near its output and

responsive to signals therein to disable the other one-way path, and control means connected both to said one path near its output and to said other path near its input, which when operated disables said switching device, said control means being adjusted so as to be unoperated when signals are impressed thereon from said one path and only echoes of said signals are impressed thereon from said other path, and to operate in response to energy received from said other path when outgoing signals received from the associated two-way circuit are present in the input of said other one-way path, and incoming signals are simultaneously present in the output of said one-way path.

2. In combination in a two-way signaling system, two two-way lines, a four-wire repeating circuit comprising two oppositely directed one-way amplifying paths connecting said lines, switching means near each terminal of the four-wire circuit and responsive to signals in the incoming one-way path thereat to disable the outgoing one-way path at that terminal, and control means at each terminal connected both to the incoming and outgoing one-way paths thereat, which when operated disables the switching means at the same terminal, said control means being adjusted to be inoperative when the difference between the energy levels of the outgoing waves in the outgoing one-way path and the incoming waves in the incoming path at the terminal is such as would be obtained by the presence of incoming signals in the latter path and only outgoing echoes of said signals in the former path, but to be operated when the difference between the energy level of waves in the incoming and outgoing paths at said terminal are such as would be obtained by the presence simultaneously of incoming signals in the incoming path and outgoing signals in the outgoing path.

3. In combination in a two-way signaling system, two two-way lines, a four-wire repeating circuit comprising two oppositely directed one-way repeating paths connecting said lines, a loss sufficient to prevent singing in said four-wire circuit normally connected in each one-way path, a switching device connected to the incoming one-way path at each terminal of the four-wire circuit, and responsive to incoming signals therein to disable the outgoing one-way path at that terminal and substantially simultaneously to remove effectively the loss in the one-way path incoming at that terminal, wave-responsive control means at each terminal having its input connected both to the output of the incoming one-way path thereat and to the input of the outgoing one-way path in front of the disabling point therein at the same terminal which when operated disables the switching means at that terminal, said control means being adjusted to be unoperated when the difference between the energy levels of the waves impressed on said control means from the outgoing and the incoming one-way paths is such as would be obtained when incoming signals are present in the latter and only echoes of said signals are present in the former, and to be operated when outgoing signals received from the associated two-way line are present in said former path.

4. The combination of claim 1 and in which said control means comprises a relay having two equal and oppositely wound windings, means responsive to the incoming waves in said one one-way path for energizing one of said windings,

means responsive to the outgoing waves in said other one-way path for energizing the other winding, means responsive to a greater magnetic force in said other winding than in said one winding for effectively disconnecting said switching device from said one one-way path, and means for initially adjusting said control means so that equal

energizing currents will be supplied to the two windings when incoming signals are present in the output of said one one-way path and only outgoing echoes of said incoming signals in said other one-way path. 5

NATHANIEL C. NORMAN.
